UNITED STATES PATENT OFFICE.

FRED W. COOLEY, OF MINNEAPOLIS, MINNESOTA, ASSIGNOR OF TWO-
THIRDS TO GEORGE T. HONSTAIN, OF MINNEAPOLIS, MINNESOTA.

FIREPROOF BUILDING.

SPECIFICATION forming part of Letters Patent No. 707,086, dated August 19, 1902.

Application filed March 25, 1902. Serial No. 99,832. (No model.)

To all whom it may concern:-

Be it known that I, FRED W. COOLEY, a citizen of the United States, residing at Minneapolis, in the county of Hennepin and State 5 of Minnesota, have invented certain new and useful Improvements in Fireproof Buildings; and I do hereby declare the following to be a full, clear, and exact description of the invention, such as will enable others skilled in 10 the art to which it appertains to make and use the same.

My present invention relates to fireproof grain-bins or similar structures, and is particularly directed to the improvement of the corner joints or columns by means of which the 15 walls of the bins are connected.

The invention is illustrated in the accompanying drawings, wherein like characters indicate like parts throughout the several views.

20 Figure 1 is a plan view, with parts broken away, showing portions of several bins embodying one form of my present invention. Fig. 2 is a vertical section on the line $x^2 x^2$ of Fig. 1, some parts being broken away. Fig. 3

25 is a detail in side elevation, showing one of the so-called "binders" removed from working position. Fig. 4 is a plan view, with parts broken away, illustrating a modified construction of the interior corner-joint shown in Fig. 1.

30 Fig. 5 is a vertical section on the line $x^5 x^5$ of Fig. 4; and Fig. 6 is a plan view, with parts broken away, illustrating a modified construction of the outer-wall corner-joint.

Referring first to the construction illustrated in Figs. 1 to 3, inclusive, the numeral 35 1 indicates the wall-tiles, which are preferably laid in successive layers with overlapped joints, and the numeral 2 indicates metal bars or beams which are interposed between 40 the successive layers or courses of tile blocks and are secured thereto by cement and, if desired, by auxiliary devices. (Not shown.) These bars 2 are preferably flat and at their inner ends are bent vertically, being prefer-

45 ably turned upward, as shown in Figs. 1 and 2 and indicated at 2^a . The ends 2^a preferably do not abut, but are spaced a considerable distance apart, preferably substantially as indicated in the drawings. The wall-tiles of the

50 1 terminate short of the ends of the bars 2, and the space left between the tiles of the

walls is filled in by a solid vertical column 3, formed of cement or concrete. The columns 3 at the junction of four intersecting walls are preferably approximately square in cross- 55 section, while those at the sides of the structure, which join together three abutting walls, are approximately triangular in cross-section, as best shown in Fig. 1. In this preferred construction the embedded ends of the bars 60 2 are tied together by diagonally-extended binders or links 4, preferably formed from round steel or iron rods, having their ends 5 turned upward and passed through perforations in the said embedded ends of the bars 65 2. The said links 4 are also embedded within the cement columns 3, and their upwardly-projecting ends serve as anchoring-pins to assist in anchoring the metal-work within the columns 3 as well as to tie together the ends 70 of the metal beams 2.

In the construction illustrated in Fig. 1 the four tie-rods 4, embedded within the interior column 3, form a rectangle and approximately endless or continuous binder, rigidly 75 securing together the four bars 2. In the outer-wall column 3 the three embedded links 4 form a triangle and operate in substantially the same manner as do the four links of the interior joint to rigidly tie together the three 80 bars 2 of the three joining walls.

In the outer-wall column illustrated in Fig. 1 narrow tile blocks 1^a are interposed between the ends of the aligned bars 2 and tile blocks 1 of the outer wall of the building. 85

To give increased strength to the columns 3, metal angle-iron bars 6 are extended vertically within the corners formed at or near the abutting ends of the bars 2, as shown in Figs. 1 and 2. These angle-iron bars 6 are embedded 90 within the cement columns 3 and need not be otherwise secured than by the cement thereof. These reinforcing bars or columns 6 would be employed only where very strong columns are desired. They are important 95 factors, however; where very heavy loads are to be sustained and would usually be employed in those columns which support the cupola in elevator construction.

The construction illustrated in Figs. 4, 5, 100 and 6 is quite similar to that illustrated in Figs. 1 and 2, but differs therefrom in the

following particulars—to wit, instead of the several links used to form a complete corner-tie endless tie bands or binders 7 are employed. In the interior column illustrated 5 in Fig. 4 the tie-band 7 is rectangular, while in the outer-wall joint illustrated in Fig. 6 the endless tie-band or binder-rod 7 is triangular. These tie-bands 7 are anchored to the several projecting ends of the bars 2 by means 10 of anchoring-pins 8, passed through perforations in the embedded ends of said bars at the corners of said tie-bands, with both ends projecting so that they are securely anchored in the cement columns 3.

15 The devices above described afford great strength and at the same time afford a cheap construction which may be very quickly put together.

It will of course be understood that various 20 modifications other than those described may be made within the scope of my invention, as herein set forth and claimed.

What I claim, and desire to secure by Letters Patent of the United States, is as follows:

25 1. The combination with adjoining walls formed by fireproof blocks and interposed metal bars or beams, of a solid corner-column formed of concrete, which metal bars have projecting ends embedded in said corner-column, and a binder embedded in said column and anchored to the embedded ends of said bars, substantially as described.

2. The combination with adjoining walls formed by fireproof blocks and interposed 30 metal bars or beams, of a solid corner-column formed of cement, which metal bars have projecting ends embedded in said corner-col-

umn, and the tie-links 4 embedded in the said column and provided with ends 5 passed through perforations in the embedded ends 40 of said bars, substantially as described.

3. The combination with adjoining walls formed by fireproof blocks and interposed metal bars or beams, of a solid corner-column formed by a solid body of cement, which 45 metal bars have projecting ends bent or extended vertically and embedded in the said concrete corner-column, substantially as described.

4. The combination with walls formed of 50 fireproof blocks and interposed metal bars or beams, of a corner-column formed by a solid body of cement, which metal bars have projecting ends bent or extended vertically and embedded in said concrete column, and a 55 metal binder rigidly tying together the embedded ends of said bars, substantially as described.

5. The combination with adjoining walls formed by fireproof blocks and interposed 60 metal bars or beams, of corner-columns formed of cement, which metal bars have projecting ends embedded in said column, a metal binder rigidly connecting the embedded ends of said bars, and the angle-iron columns placed at 65 the corners of the adjoining walls and embedded in said column, substantially as described.

In testimony whereof I affix my signature in presence of two witnesses.

FRED W. COOLEY.
